ELECTRIC IRON

Frank W. Scharf, Chicago, Ill., assignor, by mesne assignments, to McGraw Electric Company, Chicago, Ill., a corporation of Delaware

Application November 27, 1931, Serial No. 577,499

10 Claims. (Cl. 219—25)

An object of this invention is to provide a thermostatic electric iron in which the thermostatic element is almost entirely protected from direct radiations from the heating element and from the filler block.

5 This and other objects, as will hereinafter appear, are accomplished by this invention which is fully described in the following specification and shown in the accompanying drawings, in which—

10 Fig. 1 is a longitudinal section on the line 1—1 of Fig. 2 showing an iron embodying the invention;

Fig. 2 is a transverse section on the line 15 2—2 of Fig. 1;

Fig. 3 is a partial plan view slightly reduced of the center of the sole plate of Figs. 1 and 2 showing the recess, the fin, and a groove surrounding the same;

20 Fig. 4 is a partial section similar to the lower left-hand portion of Fig. 1 showing a modified form of the invention;

Fig. 5 is a view similar to Fig. 1 showing still another modification;

25 Fig. 6 is a transverse section on the line 6—6 of Fig. 5; and

Fig. 7 is a plan view of the sole plate of Fig. 5 with the thermostatic switch in place.

The embodiment shown in Figs. 1, 2 and 3 30 comprises an electric iron having a sole plate 10 and electric heating element 11, and a weight member or filler block 12 secured together by means of screws 13, 14. The sole plate 10 is provided with a centrally located recess 15 which is surrounded on two sides, and preferably the front end, with a groove 16 which need not be quite so deep as the recess itself. The groove thus provides an upwardly extending fin 16^a which in this form is preferably of the same 35 height as the top of the sole plate, so that the two may be ground off, or otherwise finished to the same height. The purpose of this fin will later be explained.

This recess is provided with a slightly raised strip 17 on which is secured a thermostatic switch 18 which has a relatively fixed switch member 19, and a movable member 20, the latter being a bi-metal strip composed of dissimilar metals having different co-efficients of expansion so that this member tends to bend and assume different positions, depending upon its temperature. It is tipped with insulation 20^a so as to prevent its making electrical contact with the sole plate. Both the members 19 and 20 carry current and act as a switch which

is closed when the two are in contact, as shown in Fig. 1.

These members are spaced from each other, and are carried upon suitable insulating strips 21 which serve also to insulate them from each other, each of these members being connected to suitable electrical terminal pins 22 carried by but insulated from the block 12 in a manner common to this art. This thermostatic switch assembly is secured in place by means of screws 10 23, a stud 24, and a nut 25. The filler block 12 is provided with an open space 12^a overlying the recess 15 and groove 16. Into this space extends a metal cover 26 which has a ground or otherwise finished face overlying and making contact with the finished face of the fin 16^a, the cover and fin preferably being of substantially the same thickness. The cover is secured in place by means of a screw 27 and a nut 28 on the stud 24.

20 A sheet metal cover 29 surrounds the filler block 12, but is spaced therefrom, and this together with a handle 30 are secured in place by means of screws 31 which are threaded into the filler block. An adjusting screw 32 is 25 threaded into the filler block and has an insulating end 33 adjustably bearing upon the fixed member 19 of the switch, this screw extending through the lower part of the handle, and having a winged knob 34 adjustably secured thereon by means of a screw 35. This adjusting knob has a pointer 36 which is adapted to swing over a radiated scale on a plate 37, which is held in place by the screws 31. This plate carries suitable stops which prevent the screw 32 from 30 making more than a half turn.

35 Thus it will be seen that the thermostatic switch may be caused to open and close for predetermined temperatures of the bi-metal strip 20, and that the points at which the switch will open and close may be changed by means of the adjusting screw 32. It is highly desirable that the temperature of the bi-metal strip 20 should be dependent almost wholly upon the temperature of the sole plate immediately beneath it, and that it should be affected as little as possible by the temperature of the heating element 11 and of the filler block 12. For this reason the metal cover 26 is placed over the thermostatic switch so as to intercept radiations from the members 11 and 12, and by absorbing these radiations transmit the heat through the fin to the sole plate.

40 At the same time the groove 16 serves another purpose, namely, of preventing heat from 45 50

the top of the sole plate directly affecting the bi-metal strip. This groove causes the heat to travel down through the sole plate, thereby affecting the face of the sole plate and raising its temperature before enough heat is radiated to the bi-metal strip to cause it to move away from the fixed member 19.

In Fig. 4 is shown a modified form of the invention in which is a sole plate 10^a and electric heating element 11^a and weight member 12^b. A thermostatic switch 18^a is mounted as before, but is covered by means of a fin 16^b which is integral with the sole plate, but which is cored out to provide a chamber 38. The operation of the device, as shown in Fig. 4, is the same as that previously described, but the fin and cover by being integral will more efficiently transmit the heat to the sole plate, thereby making doubly sure that the thermostatic switch will be affected mainly by the temperature of the sole plate immediately beneath it, and will not be affected in any great measure by the temperature of the parts above the sole plate.

In Figs. 5, 6 and 7 is shown still another modification of the invention in which there is a sole plate 10^b, a heating element 11^b, a weight member or filler block 12^c, these being secured together by means of screws 13^a and 14^a. The sole plate is made deeper and is provided with a peripheral ledge 10^c, the center of the sole plate having a recess 15^b in which is located the thermostatic switch 18^b, the one here shown being of the slow-break variety. This recess is surrounded by a groove 16^c, as in the other two forms, this groove preferably extending along both sides and the front end, as shown, thereby forming a deep fin 38. The recess 15^b is made as narrow as may be providing as little clearance as possible on the sides for the switch 18^b. This reduces the "cold spot" in the center of the iron to a very considerable degree, and protects the switch elements from direct radiation of the parts above, as will presently be explained.

The weight member 12^c is made U-shaped and is cut back at an angle so that the limits of its radiation are indicated by the lines X—X of Fig. 6. It will be noted that these lines are so chosen that they pass over the top of the thermostatic switch so that there will be no direct radiations, from the sides at least, from the filler block 12^c or from the heating element 11^b directly to the thermostatic switch. The handle 30^a is secured to the iron by means of screws 39 which are threaded into cross members 40, which are secured to the filler block 12^c, as shown in Fig. 6. Thus it will be seen that a number of modifications are provided of this automatic electric iron in which the thermostatic element is protected against direct radiations of the heated parts which lie above it, particularly the electric heating element and the filler block.

While I have shown and described but a few embodiments of my invention, it is to be understood that it is capable of many modifications. Changes, therefore, in the construction and arrangement may be made which do not depart from the spirit and scope of the invention as disclosed in the appended claims.

I claim:

1. In an electric iron or the like, a sole plate, a heating element, a weight member, a thermostatically-operated switch in series circuit with the heating element, said sole plate having a

chamber therein with walls integral with the sole plate and extending above the sole plate for substantially enclosing said switch so as to prevent direct radiation thereto from the weight member or heating element.

2. In an electric iron or the like, a sole plate, a heating element, a weight member, a thermostatically-operated switch in series circuit with the heating element, said sole plate having a recess therein for substantially enclosing said switch so as to prevent direct radiation thereto from the weight member or heating element, and a groove along each side of the recess forming a fin for carrying heat to the sole plate.

3. In an electric iron or the like, a sole plate, a heating element, a weight member, a thermostatically-operated switch in series circuit with the heating element, said sole plate having a chamber therein with walls integral with the sole plate for substantially enclosing said switch so as to prevent direct radiation thereto from the weight member or heating element, and a groove along each side of the chamber forming a fin for carrying heat to the sole plate.

4. In an electric iron or the like, a sole plate, a heating element, a weight member, a thermostatically-operated switch in series circuit with the heating element, said sole plate having an opening therein with side walls integral with the sole plate and a metal cover secured thereover for substantially enclosing said switch so as to prevent direct radiation thereto from the weight member or heating element, and a groove along each side of the chamber forming a fin for carrying heat to the sole plate.

5. In an electric iron or the like, a sole plate, a heating element, a weight member, a thermostatically-operated switch in series circuit with the heating element, said sole plate having a recess therein adapted to receive the switch, a groove along each side of the recess forming a fin, and a metal cover secured thereover to receive radiant heat from the heating element and weight member, the edges of the cover bearing upon the fin to transmit this heat thereto.

6. In an electric iron or the like, a sole plate, a heating element, a weight member, a thermostatically-operated switch in series circuit with the heating element, said sole plate having a recess therein adapted to receive the switch, a groove along each side of the recess forming a fin of the same height as the sole plate, and a metal cover secured thereover to receive radiant heat from the heating element and weight member, the edges of the cover bearing upon the fin to transmit this heat thereto.

7. In an electric iron or the like, a sole plate, a heating element, a weight member, a thermostatically-operated switch in series circuit with the heating element, said sole plate having a recess therein adapted to receive the switch, a groove along each side of the recess forming a fin, and a metal cover secured thereover to receive radiant heat from the heating element and weight member, the edges of the cover bearing upon the fin to transmit this heat thereto.

8. In an electric iron or the like, a sole plate, a heating element, a weight member, a thermostatically-operated switch in series circuit with the heating element, said sole plate having a recess therein for substantially enclosing said switch so as to prevent direct radiation thereto from the weight member or heating element, and a groove along each side of the recess, said weight member being cut back so as to have no

part alongside the recess capable of sending heat radiations direct to said thermostatic switch.

9. In an electric iron or the like, a sole plate, a heating element for heating the sole plate, said sole plate having a slot and a groove adjacent the slot forming a fin for intercepting heat rays and for transferring this heat to the lower portion of the sole plate, and a thermostat for controlling the heating element located in the slot.

10. In an electric iron or the like, a sole plate, a heating element for heating the sole plate, said sole plate having a slot and a groove adjacent the slot forming a fin of substantially the same height as the top of the sole plate for intercepting heat rays and for transferring this heat to the lower portion of the sole plate, and a thermostat for controlling the heating element located in the slot.
